UNITED STATES PATENT OFFICE.

LUTHER C. BALDWIN, OF PROVIDENCE, RHODE ISLAND.

BOBBIN-BORING MACHINE.

1,036,060.

Specification of Letters Patent. Patented Aug. 20, 1912.

Application filed April 22, 1910. Serial No. 557,085.

To all whom it may concern:

Be it known that I, LUTHER C. BALDWIN, a citizen of the United States, residing at Providence, in the county of Providence and State of Rhode Island, have invented 5 an Improvement in Bobbin-Boring Machines, of which the following description, in connection with the accompanying drawings, is a specification, like letters on the 10 drawings representing like parts.

The invention to be hereinafter described relates to bobbin boring machines, and more particularly to the means for presenting the blank to the boring devices that the latter may be enabled not only to bore the blank or bobbin uniformly, but that the bore may extend truly central thereof. The importance of this will be readily apparent to those skilled in the art, especially where the bobbins are rotated at high speed in spinning or winding yarn, where lack of axial concentricity of the bobbin bore results in an unbalanced load upon the driving spindle with the well known effect upon the yarn 25 being spun or wound.

With the above general matters in view the aims and purposes of the present invention are to provide a machine with means that will positively and accurately center 10 the blank with reference to the boring devices, all as will hereinafter more fully appear in connection with the accompanying drawings of one form of means for carrying the invention into practical effect.

In the drawings:—Figure 1 is a front elevation of a bobbin boring machine of the type described and claimed in my prior application, Ser. No. 522,102, filed Oct. 11, 1909, some of the parts being omitted for 5 clearness of illustration; Fig. 2 is a section on the line 2—2 of Fig. 1, on an enlarged scale, showing the blank positioning and centering means; and Fig. 3 is a front view of the blank positioning and centering means on an enlarged scale, the boring devices being omitted. Fig. 4 is a sectional view on the line 4—4 of Fig. 1, looking in the direction of the arrow; and Fig. 5 is a fragmentary plan view of the central portion of the machine.

The machine frame may be of any usual or desired construction, and as shown comprises a bed 1 surmounted on supporting legs 2 and providing suitable bearings for a main driving shaft 3 which may be driven by a suitable pulley 4 actuated by a belt 5 connected to a desirable source of power,

substantially as in said prior application. The boring heads A and B may be as in said application, and each comprises the upper rights 6, 6 extending from the carriage 7, and providing bearings 8, 8 for the exterior of the turning tube 9 having the teeth 10 for engaging the end of the blank and turning it during the action of the boring devices. 60 The turning tube carries a pulley 11, Fig. 1, driven by a belt 12. Within the turning tube is the centering tube 13 having fixed thereto the collar 14, between which and the sliding collar 15 is the spring 16. Secured to the machine bed 1 are the brackets 17 to each of which is pivoted one end of a lever 18, the other ends of which engage the collars 15, and connecting each of the levers 18 with the carriages 7 are the links 75 19. The carriages 7 are mounted to slide on the machine bed and one is provided with the ratchet teeth 20 engaged by the toothed segment 21 pivoted at 22 and actuated by a cam 23 on the main shaft 3, the 80 construction being such that movement of the carriages or heads toward the center of the frame causes the centering tubes 13 to advance more rapidly than the turning tubes 9, so that the centering tubes first engage and hold the blank to insure proper 85 centering thereof and then the turning tubes engage the blank positively and turn it substantially as pointed out in said prior application. Within the centering tube is 90 the non-rotatable boring tool connected to one end of a lever 25 which is actuated by a cam 26 on the main driving shaft 3, as in said application.

Disposed preferably at the rear of the 95 central portion of the machine, and sustained by the bed 1, is a hopper for containing blanks or wooden blocks, which may be of any desired shape in cross-section. In the present form of the invention the hopper 100 comprises the end supporting legs 27 projecting upward from the arms 28 to which they are secured by appropriate means such as the bolts 29, said arms 28 being carried by the brackets 30, Figs. 2 and 3, adjustable 105 longitudinally of the machine bed 1. In the present instance this longitudinal adjustability is secured by providing the bed 1 with a longitudinal groove 31, Figs. 2 and 3, in which is received the head 32 of a bolt 33 which passes through each of the brackets 30, the outer or threaded end of each bolt being provided with a nut 34, the construction being such that upon loosening the nut 34,

the brackets 30 may be moved longitudinally of the bed 1 to properly center the hopper between the boring heads A and B, as will be readily understood.

5 Adjustably connected to the supporting legs 27 of the hopper are the front and back plates 35 and 36, respectively, each having the slotted lugs 38 secured to the legs 27 by suitable bolts 39, the construction being 10 such that said front and back plates may be appropriately adjusted toward and from each other to properly accommodate blanks from which the bobbins are to be made.

Projecting rearwardly from the upper 15 portion of the bracket 52, adjustably secured to the machine bed by the bolts and nuts 32' and 33', Fig. 3, is a guideway 40, Fig. 2, for a slide 41, the forward end of which is downturned to form a central foot 42 constituting the supporting element for the 20 lower blank supporting means, said blanks being designated by 43. The central foot 42 has extended vertically therethrough an upright or stud 44, which may be secured in 25 adjusted position by means of a set screw 45.

Surmounting the upright or stud 44 is a centering block 46 through which passes a block supporting rod 47 appropriately secured by a set screw 48, or other suitable 30 means. The end portions of the block supporting rod 47 carry blank supporting rests or blocks 49 on which the end portions of the lowermost blank 43 may rest, the construction being such that the blank supporting 35 blocks 49 may be simultaneously adjusted vertically by the single adjustment of the upright or stud 44 carried by the central foot 42 of the slide 41. Each of the blank supporting blocks 49 may be adjustably secured longitudinally of the supporting rod 47 by appropriate means, as the set screws. 50, Figs. 1 and 3. Thus not only are the blocks 49 simultaneously adjustable vertically to bring the axial center of the blank 45 sustained thereby into the axial center of the boring heads when the blank is moved into position between them, as hereinafter described, but each block is itself adjustable on the supporting rod to properly sustain 50 the end portions of the blank.

Pivotedly mounted at 51, Figs. 2 and 3, on a portion projecting downward from the adjustable bracket 52, is a slide actuator 53, the upper end of which is slotted at 54 to engage a pin 55 connected to the slide 41, the lower arm of said actuator being provided with suitable rolls 56 and 57 for engagement with cams 58 and 59, respectively, secured to the main driving shaft 3, the construction 55 being such that the actuator 53, and perforce the slide 41, is positively moved forward and backward to carry the lowermost blank 43 into central position between the boring heads and then retreat after the blank has 60 been engaged by the boring head centering

tube. As the slide 41 is thus moved to position a blank, the upper surface thereof supports the blanks above it, as will be readily understood. To limit the forward movement of the actuator and prevent the blank 70 being carried beyond the axial centers of the boring heads, the actuator is provided with an adjustable stop 60, which on the forward movement of the slide and actuator may contact with the bed 1 and thus prevent over- 75 throw movement by the cam 59.

Extending forward from the supporting legs 27 of the hopper and consequently adjustable longitudinally of the machine bed with the hopper, are the brackets or arms 61 80 which provide bearings for a shaft 62 which carries the blank engaging fingers 63, Figs. 2 and 3, the ends 64 of which are preferably turned, as shown, and provided with rolls 65 or other blank engaging means for engaging the front surface of the lowermost blank in the hopper, the construction being such that when the lowermost blank in the hopper is to be moved between the boring heads, the fingers 63 will take position as indicated by dotted lines in Fig. 2, and move positively with the slide 41 to positively position the blank, as will presently appear. The shaft 62 is provided with a pinion 66 operatively engaged with a pinion 67 supported by one of the brackets 61, said pinion 67 being itself operatively engaged by a movable rack 68 on the actuator 69, the construction being such that as the actuator 69 is moved endwise, vertically in the present 100 case, the pinions 67 and 66 will be turned to carry the blank engaging fingers 63 to and from the dotted line position in Fig. 2. The actuator 69 extends downward and has a projection or toe 70 which rides upon a cam 105 71 secured to the main shaft 3, and is normally under the influence of a spring 78 tending to pull the actuator downward, Fig. 2. It will be noted that the cam 77 has a groove or cut away portion 79, Fig. 2, and that the remainder of the cam is substantially circular, the construction being such that when the cut away portion of the cam comes under the projection or toe 70 of the actuator, the latter will drop in response to 110 the spring 78 and carry the fingers 63 into contact with the front surface of the lowermost blank in the hopper. This action of the actuator occurs after the beginning of the forward movement of the slide 41 and as 120 the latter moves the blank forward the fingers 63 bear forcibly but yieldingly against the front of the blank, until when the centering tube 13 has engaged the ends of the blank, the projection or toe 70 of the actuator 125 is lifted by the cam 71 into its upper or inoperative position, as indicated by full lines in Fig. 2.

From the construction described it will be noted that while the end portions of the 130

lowermost blank are sustained by the blocks 49 to properly position the blank axis vertically in alignment with the axis of the centering tubes of the boring heads, the fingers 63 insure the proper lateral or horizontal position of the axis and prevent deflection thereof toward the front or rear of the axial center of the centering tubes, with the result that the blank is correctly positioned between the boring heads by the slide and fingers, until the centering tubes 13 engage the ends of the blank, whereupon the fingers are moved to an upper or inoperative position, as shown by full lines, Fig. 2, and the slide 5 retreats.

It will be obvious that changes in details of structure may be made within the true scope of the invention which is definitely set forth by the claims. It will be also apparent that the pinions 62 and 67 may be housed in a suitable casing to prevent clogging by dirt or pieces of wood, and that a guide 80 may be provided for the actuator at its upper portion, if desired.

What is claimed is:

1. In a bobbin boring machine, the combination of bobbin boring means, a hopper for containing a series of blanks to be bored, a slide for moving blanks from the hopper, blank supporting blocks carried by the slide, means for adjusting said blocks toward and from each other to accord with the length of blanks to be bored, fingers mounted independently of the slide and separated a distance somewhat less than the length of the blank, means for moving said fingers into contact with end portions of the blank to hold the blank on the slide as the latter moves the blank between the boring heads, said means yielding with the blank as it is moved, and means to positively move the fingers in the same direction into inoperative position.

2. In a bobbin boring machine, the combination of bobbin boring means, a hopper for containing blanks to be bored, a slide for moving a blank from the hopper, fingers pivotally mounted above the plane of the slide movement and in vertical planes passing through the end portions of the blank to be moved by the slide, means to turn said fingers simultaneously in their respective planes to engage end portions of the blank prior to movement of the blank from the hopper and yield to allow the fingers to move with the blank as it is placed in operative relation to the boring means, and means to then move the fingers into an inoperative position.

3. In a bobbin boring machine, the combination of bobbin boring means, a hopper for containing a series of blanks, a slide for moving a blank from the hopper to boring position, a pair of fingers pivotally mounted at one end at the front of the hopper above

the plane of movement of the slide and adapted to engage the blank at the end portions thereof, means for swinging the fingers about their end pivotal mounting into contact with the front of the blank while in the hopper to hold it on the slide as the latter moves the blank from the hopper to boring position, said fingers being moved by the blank, and means to swing the fingers upward away from the blank.

4. In a bobbin boring machine, the combination of boring heads, a hopper disposed between said heads for containing a series of blanks, means to move the lowermost blank from the hopper to a position between the boring heads, a plurality of fingers pivotally supported by the hopper above the plane of movement of said means to engage the blank and hold it on said moving means as the latter moves the blank to position between the boring heads, said plurality of fingers being mounted and movable independent of the said means, and means normally holding said plurality of fingers in inoperative position and permitting them to move into operative position and then move with the blank.

5. In a bobbin boring machine, the combination of boring heads, a hopper for containing blanks to be bored, means for moving a blank from the hopper to a position between the boring heads, fingers to engage the front of the blank adjacent its end portions while it is being moved by said means, a rack and pinion for moving the fingers into and out of contact with the front of the blank, a spring for moving the rack to carry the fingers into contact with the blank, and a cam for moving the rack to carry the fingers away from the blank and permitting the fingers to be moved in an opposite direction against the tension of said spring with and by the blank as it is moved by the said means after it has been positioned between the boring heads.

6. In a bobbin boring machine, the combination of bobbin boring means, a hopper for containing blanks to be bored, a slide for moving blanks from said hopper, a rod carrying blocks carried by said rod and on which the lowermost block in the hopper rests, and fingers to engage the front of the blank and hold it on said blocks as it is moved to position for the action of the boring means.

7. In a bobbin boring machine, the combination of bobbin boring means, a hopper for containing blanks to be bored, a slide for moving blanks from said hopper, a rod carried by the slide, blank supporting blocks carried by said rod, means for securing the blocks on said rod in position to sustain the end portions of the lowermost blank in the hopper, and fingers to engage the front of the blank and hold it on said blocks as it is

moved to position for the action of the boring means.

8. In a bobbin boring machine, the combination of bobbin boring means, a hopper for containing the blank to be bored, means for moving blanks from the hopper to position for the action of the boring means, a plurality of fingers to engage the front of the blank and hold it centered on the said means 10 as it is moved, a rack and pinion for moving the fingers, a cam having a cut away portion and acting normally on said rack to maintain said fingers in inoperative position, and a spring for moving the fingers into 15 contact with the blank when the cut away portion of the cam is in operative position with relation to the rack.

9. In a bobbin boring machine, the combination of boring heads, a hopper to contain blanks to be bored, a feed slide carrying a rod at its end portion extending longitudinally of the blanks in the hopper, blocks mounted on said rod to support and carry the lowermost blank in the hopper, 20 fingers adapted to engage the blank on said blocks and hold it in position thereon as the feed slide moves the blank into position between the boring heads, and means for adjusting said rod and with it the blocks 25 carried thereon to properly position blanks of varying thickness between the boring heads when they are moved by the slide between said heads.

10. In a bobbin boring machine, the combination of boring heads, a hopper to contain blanks to be bored, a feed slide having a downturned end portion, a stud carrying a block secured to said end portion, means for adjusting said block transversely of the 30 plane of movement of the slide, a rod supported by said block, blank sustaining blocks carried by said rod on opposite sides of said first named adjustable block and adjustable toward and from each other, and fingers for 35 holding the blank on said blocks as the feed slide moves the blank to position between the boring heads.

11. In a bobbin boring machine, the combination of boring heads, a hopper for blanks to be bored, a feed slide, blocks carried by the feed slide for supporting the blank as it is moved by said slide, means for adjusting said blocks toward and from each other to adapt them to different length of 40 blanks, and means for adjusting said blocks transversely of the plane of slide movement to adapt them to different thickness of 45 blanks.

12. In a bobbin boring machine, the combination of boring heads, a hopper for blanks to be bored, said hopper having its 50 end portions adjustable toward and from

each other to accommodate blanks of varying lengths, a feed slide for moving a blank from the hopper to a position between the boring heads, a finger disposed adjacent each end of the hopper and adjustable therewith to engage the end portions of a blank and hold it on the slide as the latter moves the blank into boring position, and means normally holding said fingers in inoperative position and permitting them to engage a blank before it is moved from the hopper.

13. In a bobbin boring machine the combination of boring heads, a hopper for blanks to be bored, the end portions of said hopper being adjustable toward and from each other to accommodate blanks of different lengths, a feed slide, a plurality of fingers for engaging a blank and moving with it as the feed slide places it in boring position, a shaft carrying said fingers in separate relation lengthwise of the blank, and means for turning said shaft and holding the fingers in normal inoperative position and permitting said fingers to engage the blank before it is moved from the hopper.

14. In a bobbin boring machine, the combination of boring heads, a hopper for blanks to be bored, the end portions of said hopper being adjustable toward and from each other to accommodate blanks of different lengths, a feed slide, a plurality of fingers for engaging a blank and moving with it as the feed slide places it in boring position, a shaft carrying said fingers in separate relation lengthwise of the blank, said shaft being sustained from the end portions of said hopper, and means for turning said shaft and holding the fingers in normal inoperative position and permitting said fingers to engage the blank before it is moved from the hopper.

15. In a bobbin boring machine, the combination of boring heads, a hopper, a feed slide to take a blank from the hopper and position it for boring, a finger for engaging each end of the blank and holding it on the feed slide as the latter moves the blank to said position, a shaft supported from the hopper and carrying said fingers, yielding means for causing the fingers to so act, and positive means for swinging the fingers in a direction opposite the retreating movement of the feed slide after the blank has been positioned.

In testimony whereof, I have signed my name to this specification, in the presence of two subscribing witnesses.

LUTHER C. BALDWIN.
